US0D1029259S

(12) **United States Design Patent** (10) **Patent No.:** **US D1,029,259 S**
(45) **Date of Patent:** **** May 28, 2024**

(54) **PORTION OF A MEDICAL DEVICE**

(71) Applicant: **New Wave Endo-Surgical Corp.**,
Coconut Creek, FL (US)

(72) Inventors: **Ricardo Gomez**, Lighthouse Point, FL (US); **Theo Dienes**, Coconut Creek, FL (US); **Sandy Heck**, Los Angeles, CA (US); **Juan Carlos Diaz**, Coconut Creek, FL (US)

(73) Assignee: **New Wave Endo-Surgical Corp.**,
Coconut Creek, FL (US)

(**) Term: **15 Years**

(21) Appl. No.: **29/806,037**

(22) Filed: **Aug. 31, 2021**

(51) LOC (14) Cl. **24-02**

(52) U.S. Cl.

USPC **D24/147**

(57) **CLAIM**

The ornamental design for a portion of a medical device, as shown and described.

DESCRIPTION

FIG. 1 is a front perspective view of a portion of a medical device showing my new design in a first position of use; FIG. 2 is a rear, distal (tip) end perspective view thereof; FIG. 3 is a front plan view thereof; FIG. 4 is a rear plan view thereof; FIG. 5 is a right, side plan view thereof; FIG. 6 is a left, side plan view thereof; FIG. 7 is a proximal end view thereof; FIG. 8 is a distal end view thereof; FIG. 9 is a rear, distal end, perspective view thereof; FIG. 10 is an additional front, distal end, perspective view thereof; FIG. 11 is a front perspective view thereof in a second position of use; FIG. 12 is a rear, distal end, perspective view thereof; FIG. 13 is a front, plan view thereof; FIG. 14 is a rear, plan view thereof; FIG. 15 is right, side plan view thereof; FIG. 16 is a left, side plan view thereof; FIG. 17 is a proximal end view thereof; and, FIG. 18 is a distal end view thereof.

The unshaded regions within the shaded area demarcated by broken lines form no part of the claimed design. The broken lines showing of the remainder of the medical device represents unclaimed subject matter and forms no part of the claimed design.

1 Claim, 16 Drawing Sheets
